THROTTLE VALVE FOR PNEUMATIC TOOLS

William A. Smith, Sr., Athens, Pa., assignor to
Ingersoll-Rand Company, Jersey City, N. J., a
corporation of New Jersey

Application August 12, 1936, Serial No. 95,497

2 Claims. (Cl. 121—35)

This invention relates to throttle valves, and more particularly to a throttle valve for pneumatic tools.

One object of the invention is to reduce the overall length of the pneumatic tool.

Another object is to assure thorough lubrication of the throttle valve and its seating surfaces.

Other objects will be in part obvious and in part pointed out hereinafter.

10 In the drawings accompanying this specification and in which similar reference numerals refer to similar parts,

Figure 1 is an elevation, in section, of a rock drill equipped with a throttle valve constructed in accordance with the practice of the invention,

15 Figures 2, 3 and 4 are transverse views taken through Figure 1 on the line 2—2 showing the throttle valve in different controlling positions.

Figure 5 is a view similar to Figure 1 showing a modified form of the invention, and

20 Figure 6 is a transverse view taken through Figure 5 on the line 6—6.

Referring more particularly to the drawings, 25 20 designates, in general, a pneumatic tool of the percussive type adapted to actuate a working implement 21.

The tool 20 comprises a cylinder 22 and front and back heads 23 and 24, respectively, which may be secured to the cylinder by the usual side bolts 25. Interposed between the cylinder 22 and the front head 23 is a front cylinder washer 26 which forms a closure for the front end of a piston chamber 27 in the cylinder and also serves as a guide for the stem 28 of a hammer piston 29 reciprocable in the piston chamber for delivering blows to the working implement 21.

30 In the stem 28 are a series of flutes 30 to accommodate ribs 31 in a chuck 32 in the front head 23 and wherewith the working implement 21 is slidably interlocked. The cylinder 22 in the present instance is provided with a free exhaust port 33 which is controlled by the piston 29.

35 In the rearward portion of the cylinder 22 is an enlarged bore 34 for the accommodation of pressure fluid distributing valve mechanism 35 and rotation mechanism 36. The distributing valve mechanism is arranged adjacent the rear end of the piston chamber 27. It comprises a valve chest consisting of a pair of plates 37 and 38 of which the plate 37 serves as a closure for the rear end of the piston chamber and has an inlet passage 39 which opens into the rear end of the piston chamber. An inlet passage 40, in the plate 37 and in the cylinder 22, leads to the front end of the piston chamber 27.

Both inlet passages communicate with a valve chamber 41 defined by the plates 37 and 38 and containing a distributing valve 42 of the oscillatory plate type for controlling the inlet passages 39 and 40.

5 The rotation mechanism 36 is seated upon the plate 38 and comprises a ratchet ring 43 which encircles the head 44 of a rifle bar 45 extending through the valve mechanism and interlockingly engaging the piston 29. The head 44 carries the usual spring pressed pawls 46 to engage teeth 47 on the inner surface of the ratchet ring 43 for holding the rifle bar against rotary movement during the rearward stroke of the piston 29 and thereby enable the piston to describe a partial revolution, in a manner well known, for rotating the working implement 21 to a new position between blows of the hammer piston.

10 Preferably a plate 48 is interposed between the ratchet ring and the back head 24 to transmit the clamping pressure of the back head to the elements housed in the bore 34. The plate 48, the ratchet ring 43 and the plate 38 are provided with supply passages 49 for conveying pressure fluid to the valve chamber 41, and the pressure fluid is supplied to the supply passages 49 by a supply chamber 50 in the back head 24 and communicating with a supply conduit 51 through a port 52.

15 In accordance with the practice of the invention the front end of the chamber 50 also serves as a chamber for a throttle valve 53 consisting of a flat plate having an axial bore 54 to receive a boss or spindle 55 on the front head. The front end of the throttle valve 53 is seated upon a seating surface 56 on the rear end of the plate 48, and the rearward surface of the throttle valve constitutes a pressure area 57 against which pressure fluid in the chamber 50 acts constantly to maintain the throttle valve seated firmly against the plate 48.

20 In the throttle valve are a series of ports 58 which, when the throttle valve occupies one controlling position, register with the supply passages 49 to admit pressure fluid thereto from the chamber 50. The ports 58 will also register with passages 59 in the plate 48 and the ratchet ring 43 and opening into an annular groove 60 in the periphery of the ratchet ring.

25 25 The annular groove 60 communicates with a blower passage 61, in the cylinder 22 and the front cylinder washer 26, leading to an internal annular groove 62 in the front cylinder washer. The passages 59 and 49 are arranged on the same circle and are staggered with respect to each 30 35 40 45 50 55 60 65 70 75 80 85 90 95 100

other so that either set of passages may be readily communicated with pressure fluid supply by merely shifting the valve 53 a slight distance.

The means provided for actuating or rotating the valve 53 comprises a shaft 63 journalled in the back head 24 and having a flange 64 that engages a shoulder 65 in the back head to prevent rearward movement of the shaft. The flange 64 carries a stem 66 which is arranged eccentrically with respect to the shaft 63 and extends into a notch 67 in the periphery of the valve 53. The opposite end of the shaft is in the form of a reduced extension 68 upon which is mounted a lever 69 for rotating the shaft 63. The end 68 is threaded for the accommodation of a nut 70 whereby the lever 69 is clamped firmly to the shaft 63.

The operation of the device is as follows: Whenever it is desired to set the distributing and percussive elements of the pneumatic tool in operation the throttle valve is rotated, by means of the lever 69, to a position in which the ports 58 register with the passages 49, as illustrated in Figure 3. Pressure fluid is thereby admitted into the valve chamber 41 and distributed to the ends of the piston chamber by the valve 42 to cause reciprocation of the piston 29.

In the event that such means as may be provided for normally maintaining the drill hole free of detritus prove inadequate for that purpose, and in consequence of which cuttings accumulate in the drill hole, the throttle valve 53 is rotated to another controlling position in which the ports 58 register with the passages 59. This position is illustrated in Figure 4. Pressure fluid will then flow directly from supply into the annular groove 62, thence through the flutes 30, the chuck 32 and through the working implement into the drill hole to expel the cuttings therefrom. After the drill hole has been cleansed the throttle valve 53 may again be returned to its initial position, or to a neutral position in which the ports 58 are out of registry with the passages 49 and 59.

In the modified form of the invention illustrated in Figures 5 and 6 the ratchet ring designated 71 is recessed externally to provide a supply chamber 72 for pressure fluid, and in the chamber 72 is arranged the throttle valve 73 comprising a cylindrical extension 74 that encircles the ratchet ring and bears thereagainst. On the front end of the extension 74 is an external lateral flange 75 which seats upon a seating surface 76 on the ratchet ring. The rearward surface 55 of the flange 75 constitutes a pressure area 77 against which pressure fluid in the chamber 72 acts to press the flange 75 against the seating surface 76. The flange, as in the form of the throttle valve previously described, is also provided with a series of ports 58 to register with the supply passages 49 and the blower passages 59.

In the present instance the valve actuator is arranged in the same transverse plane as the flange 75. It comprises a worm 78 of which the thread is of a self-locking pitch and engages teeth 79 on the periphery of the flange 75. The ends of the worm are provided with stems 80 and 81 of which the latter is journalled in a plug 82 threaded into the back head 24, and the stem 80 is journalled directly in the back head and carries a reduced extension 83 to accommodate a lever 84 which is secured in position on the stem 80 by a nut 85.

In the operation of this form of valve the worm 78 is rotated by means of the lever 84 to bring the ports 58 into registry with the passages 49 or 59, depending upon whether it be intended to supply pressure fluid to the distributing valve 42 for operating the percussive element or to the blower passages for cleansing the drill hole. The worm is rotated in one direction to communicate the 20 passages 49 with pressure fluid supply and in an opposite direction to supply pressure fluid to the passages 59. By reason of the fact that the threads of the worm are of a self-locking pitch the throttle valve 73 will remain securely in 25 placed position undisturbed by the vibrations resulting from the operation of the rock drill.

In practice, the present invention has been found to be highly desirable in pneumatic tools. By arranging the throttle valve in the path of 30 flow of the pressure fluid conveying lubricant for the bearing surfaces of the tool the throttle valve will be constantly supplied with an ample amount of lubricant, thereby preventing sticking of the throttle valve and rendering it particularly easy 35 to manipulate.

I claim:

1. In a throttle valve for pneumatic tools, the combination of a casing and a pressure fluid distributing element, a passage to convey cleansing 40 fluid for cleansing a hole being drilled, a supply passage for conveying pressure fluid to the distributing element, a rotary plate throttle valve in the casing having a port to afford communication between pressure fluid supply and the 45 passages, and means for rotating the throttle valve to place the port selectively in registry with the passages.

2. In a throttle valve for pneumatic tools, the combination of a casing and rotation mechanism 50 therein including a ratchet ring, a seating surface on the ratchet ring, a pressure fluid distributing element, a supply passage for conveying pressure fluid to the distributing element, a passage for conveying cleansing fluid for cleansing 55 a hole being drilled, an annular plate throttle valve on the seating surface encircling the ratchet ring and having a port to selectively effect communication between pressure fluid supply and the passages, and means for actuating 60 the throttle valve.

WILLIAM A. SMITH, SR.
